UNITED STATES PATENT OFFICE.

WALTER HENRY DRAKE AND JAMES JOSEPH DRAKE, OF CLEVELAND, OHIO.

APPARATUS FOR MAKING ARTICLES FROM PULP.

1,326,582.

Specification of Letters Patent. Patented Dec. 30, 1919.

Application filed October 16, 1918. Serial No. 258,463.

To all whom it may concern:

Be it known that we, WALTER H. DRAKE and JAMES J. DRAKE, citizens of the United States, residing at Cleveland, in the county 5 of Cuyahoga and State of Ohio, have invented certain new and useful Improvements in Apparatus for Making Articles from Pulp; and we do hereby declare the following to be a full, clear, and exact description of the invention, such as will enable others skilled in the art to which it appertains to make and use the same.

This invention relates to an apparatus for producing articles from pulp, and has for 15 an object to produce a mechanism adapted to automatically form articles from pulp and to partially or completely dry out the fluid carriage and automatically dump or automatically drop the completed articles.

20 The further object of the invention is to produce an improved structure adapted to carry out the processes described in co-pending application, Serial No. 213,820, filed January 25, 1918, renewal on Serial No. 25 177,580, filed June 28, 1917.

The further object of the invention is to 30 provide a master unit adapted to actuate a plurality of attached units for accomplishing the same purpose from a single timing mechanism.

The further object of the invention is to 35 provide an improved means for closing the sides and bottom of a foraminous mold with improved means for introducing pulp and a drying fluid into the foraminous mold.

With this and other objects in view the 40 invention comprises certain novel constructions, combinations and arrangement of parts as will be hereinafter more fully described and claimed.

In the drawing Figure 1 is a view of the 45 improved master unit in side elevation, certain parts being broken away to show the structure.

Fig. 2 is a top plan view of the master 50 unit the reciprocating rods being sectioned to remove the overhanging parts and showing on line 1-1 the section of Fig. 1.

Fig. 3 is a transverse sectional view of the master unit taken substantially on line 55 3-3 of Figs. 1 and 2.

Fig. 4 is a top plan detail view of the 60 rotating valve member, parts being broken away to show the air passage.

Fig. 5 is a top plan view of the sta-

tionary valve seat member, parts being broken away to show the air inlet.

Figs. 6, 7, 8, 9 and 10 are respectively diagrammatic views showing the progressive steps or movement of the oscillating valve member and the registry of the several parts.

Fig. 11 is a detail sectional view transversely through the foraminous mold and 65 operating parts.

Fig. 12 is an inverted plan view of the top member of the mold with the foraminous sheet removed.

Fig. 13 is a view in elevation of the inner surface of the side mold with the foraminous sheet removed.

Fig. 14 is a view in plan of the bottom of the mold with the foraminous sheet removed.

Figs. 15 and 16 are respectively side and 75 end elevation of the mold operating arms. Like characters of reference indicate corresponding parts throughout the several views.

The improved apparatus which forms the 80 subject matter of this application comprises a frame, bed, or base 20 of any approved form or construction and supported in any approved manner as by the legs 21.

Upon the base 20 bearings 22 and 23 are 85 erected journaling the main driving shaft 24. The driving shaft 24 receives power from any source not shown, an extension being provided for the receipt of the driving element or to be coupled to the driving shaft of any other master unit in duplicate of the unit disclosed in this application and not shown.

The shaft 24 carries cams 25, 26 and 27 90 provided with the necessary cam grooves for performing the functions hereinafter described.

Erected also upon the base 20 is a bracket 95 28 from which is suspended a foraminous mold and upon which is imposed the valve mechanism. The foraminous mold is attached to the bracket 28 by securing the top member 29 thereto by means of bolts or the like inserted through the hole 30, the top 100 section of the mold being rigid with the bracket 28 carrying the inlet tube 31, which is likewise rigid with the bracket 28.

The side walls of the mold are composed of members 32 as indicated at Fig. 13 in 110 elevation which members are provided with necessary means for attaching to the arms

33. As shown at Fig. 11 this means for attaching members comprises substantially a triangular structure, but it is to be understood that the form of the structure permitting attachment to the arm 33 depends upon the shape of the mold when completed, the mold as shown being square in form. The arms 33 are rigidly carried upon shafts 34 and 35 which are geared together and 10 act synchronously by the segments 36 and 37 respectively. The shaft 34 is oscillated in its bearings in the bracket 28 by means of the lever 38 and is connected by means of a bolt 39 with an ear 40 carried upon the 15 bar 41. The bar 41 is pivoted upon the upper extremities of arms 42 and 43, the latter of which is provided with a cam roller 44 engaging with and operated by the cam 26. The arms 42 and 43 are at 20 their lower extremity pivoted upon the base 20 so that as the arm 43 is oscillated by the cam 26, the bar 41 has a movement in parallelism with the base 20. Rotation of the cam 26 and reciprocation of the bar 41 25 serves to oscillate the shaft 34 and through the geared connection the shaft 35, which shafts carrying the mold sections tends to open and close such molds alternately.

The bottom mold comprises a bottom 30 plate 45 shown in detail at Fig. 14 with the foraminous covering removed. The plate 45 is carried by the arm 46 mounted upon the shaft 47 whereby when such shaft 47 is oscillated the bottom plate 45 is moved into 35 and out of closed position. To limit the upward movement of the plate 45 carried by the arm 46 and properly position such plate and complete the mold structure a limiting stop 48 is provided which being adjustable 40 abuts against the adjacent portion of the bracket 28.

To oscillate the shaft 47 of the bottom mold section a lever 49 is carried upon said shaft and provided with an upstanding 45 spring controlled finger 50. From the finger 50 an arm 51-pivoted thereon extends transversely across the base and is rigidly connected to the shaft 53. The shaft 53 journaled in the base 20 is provided with 50 the arm 54 carrying a cam roller 55 engaging with and operated by the cam 25. As the cam 25 rotates the shaft 53 is oscillated reciprocating link 51, and oscillating thereby lever 49, the shaft 47 raising and 55 lowering the bottom plate 45 of the mold. The grooves of the cams 25 and 26 are such that the bottom plate 45 is actuated to drop and the side plates 32 to open simultaneously whereby the article within the mold is 60 dropped therefrom and to close simultaneously to receive a further charge of pulp.

To control the introduction of pulp a valve base structure 56 is erected upon that part of the bracket 28 overhanging the mold 65 and carried thereon in any improved man-

ner as by the bolts 57 in holes 58. The valve base structure 56 is provided at its upper limit with a valve face shown at 59, especially at Fig. 5. It is provided with duct 60 connecting with the tube 31 which extends downwardly into the mold. It is also provided centrally with an opening 61 to receive a spindle 62 and with an air port 63 receiving air through the tube 64.

Upon this face 59 a valve member 65 is 75 provided, journaled upon the spindle 62, a spring 66 and a tension nut 67 being provided for insuring intimate but yielding contact between the valve member 65 and the base member 56. The valve member 65 80 has an opening 68 arranged to receive a pipe 69 which is connected by an approved flexible piping with a source of pulp supply not shown. The valve member 65 is also provided with a passage 70 having a 85 port 71 positioned at times to register with the port 63 of the base member and outlet ports 72, 73 and 74 also communicating with the passage 70.

The co-action of the valve parts and ports 90 are shown diagrammatically at Figs. 6-10 inclusive. At Fig. 6 port 60 and 68 are shown in registry whereby the pulp from the supply pipe 69 is introduced by gravity through the valve structure into the mold. 95 The rotation of the valve member in the position shown by the arrow first cuts off the pulp supply by moving ports 68 and 60 out of registry, the members being in initial position as shown in Fig. 7 not permitting 100 the introduction either of air or pulp. As the valve member 65 advances further in the direction indicated by the arrow, the air ports 63 and 70 are brought into communication but not into complete registry. At 105 the same time outlet port 74 is brought over the port 60 whereby air from the air passage passes through the port 71 and port 74 to the passage 60 and into the mold. The port 74 is comparatively small permitting the introduction of a small volume 110 of air. As the valve member 65 advances further however the port 73 also passes over the port 60 and a greater volume of air is admitted. The further advance brings all 115 three ports 72, 73 and 74 over port 60 whereby the maximum volume of air is passed into the mold and forces out the fluid carriage leaving the pulpy mass adhering to the walls of the mold. It is designed to employ heated air or possibly superheated steam whereby the fluid carriage is initially expelled and the pulpy adhering mass is likewise completely or partially dried.

To oscillate valve member 65 the said member is provided with a segmental rack 75 engaging the rack 76 carried upon the bar 77. The bar 77 is pivoted upon the upper extremity of arms 78 and 79 which 120

correspond to the arms 42 and 43 and are similarly pivoted on the base 20. The arm 79 is also provided with a cam roller 80 engaging with and operated by the cam 27. As the cam 27 rotates the bar 77 is given the necessary reciprocating movement to oscillate the cam member 65 with the required progression. As all of the cams 25, 26, and 27 are carried rigidly upon the same shaft 24, it is obvious that all of the said cams and the ports actuated thereby will operate in timed relation whereby the opening and closing of the mold is properly timed in regard to the introduction of pulp or air into the mold so that the mold will be closed at the times the valve members are in position shown progressively at 6-10 inclusive and to open only when the valve has been returned by the return reciprocation of the bar 76 to the initial position shown at Fig. 7. Both of the bars 41 and 77 as well as the shaft 53 are arranged for connection with the extremity of other shafts and bars whereby the additional units consisting of other molds and mold operating devices may be attached thereto and all driven from the master unit disclosed in this application.

The several mold parts comprise a top 29, the sides 32 and the bottom 45 and are covered with any approved foraminous material 81, the foraminous material being supported upon the knife edges interposed between the holes drilled through the several plates permitting the expulsion of the fluid carriage through the foraminous sheets and through the holes provided in the several mold sections. It is obvious that as the pulp suspended in the fluid carriage is introduced into the mold a sufficient amount of fluid carriage will be expelled initially to permit the deposit of the required sheet of pulp upon the interior of the mold walls. When the pulp has been deposited in a sufficient quantity and thickness the further introduction of pulp is suspended by the action of the valve member 65, and air or other drying fluid is introduced into the mold to complete expulsion of the fluid carriage and compact the pulp adhering to the mold walls and to dry out or expel the remaining watery fluid remaining in the adhering pulp. In ordinary use the pulp discharge will be in comparatively thin sheets and the amount of the watery fluid remaining in the adhering pulp will be small in quantity whereby the air, super-heated steam or other drying fluid will quickly and readily expel such air leaving the pulp mass 60 in substantially a completely dried form.

We claim:

1. The combination with a mold having separable sections of a cam controlled reciprocating bar, means connecting the reciprocating bar with and actuating said mold sec-

tions, means to operate said cam and means for connecting the bar with the like bar of a similar unit.

2. The combination with a mold having separable side sections and bottom sections, means for actuating one of said side sections, means connecting the side sections whereby the actuation of said first mentioned side section simultaneously actuates the other of said side sections, means for actuating said bottom section and means for synchronizing said actuating means.

3. The combination with a mold having pivotally supported separable sections of a cam-controlled reciprocating bar, means connecting the reciprocating bar with and actuating said mold sections, means to operate said cam and means to attach a second like bar to the said first mentioned bar.

4. The combination with a mold having pivotally supported separable side sections having engaging toothed segments, a reciprocating bar, means connecting one of said side sections with and to be actuated by the reciprocating bar, a driven part, a cam to reciprocate the bar on the driven part, and means to attach a second like bar to be driven from the first mentioned bar.

5. The combination with a mold having pivotally supported side and bottom separable sections and a reciprocating bar, means connecting the side sections with and to be oscillated by the reciprocating bar, an oscillating shaft, means to actuate the bottom section from the oscillating shaft and means to operate simultaneously said reciprocating bar and oscillating shaft.

6. The combination with a foraminous mold comprising separable top, bottom and side sections, of a bar mounted to reciprocate, a shaft mounted to oscillate, means for connecting the reciprocating bar to said side sections and the oscillating shaft with the bottom section, a valve structure adapted to control the introduction of pulp and a drying fluid to the mold and means for actuating the bar, the shaft and the valve structure in timed relation.

7. The combination with a mold comprising a stationary top section, separable side and bottom sections and a reciprocating bar, an oscillating shaft, means connecting the bar and shaft with and to actuate the side and bottom mold sections simultaneously, a source of pulp supply, a source of drying fluid supply, a valve structure adapted to control successively the introduction of pulp and drying fluid into the mold, a driving part adapted to actuate the bar, the shaft and the valved structure in timed relation.

8. The combination with a driven shaft having a plurality of cams mounted thereon, of a mold having a separable top, side and bottom sections, said side and bottom sections being pivotally supported and means

coöoperative with said cams to oscillate said side and bottom sections simultaneously.

9. The combination with a driven shaft having a plurality of cams mounted thereon, 5 of a mold having separable top, side and bottom sections, said side and bottom sections being pivotally supported and means coöoperative with said cams to oscillate said side and bottom sections simultaneously 10 comprising a reciprocating bar connected to said side sections and an oscillating shaft secured to said bottom section.

10. The combination with a driven shaft having a plurality of cams mounted thereon, 15 of a mold having separable top, side and bottom sections said side and bottom sections being pivotally supported and means coöperative with said cams to oscillate said side and bottom sections simultaneously comprising 20 a bar reciprocated by one of said cams and connected to one of said side sec-

tions, engaging segmental members secured to said side sections, a shaft, means connecting said shaft and another of the cams whereby the shaft is oscillated, and means 25 connecting said shaft and the bottom section of the mold.

11. The combination with a driven shaft having a plurality of rotatable elements mounted thereon; of a mold having a separable top section, side sections and bottom section, means for coöperation with said rotatable elements for simultaneously actuating said sections to open and close the mold and means for connecting said actuating 35 means to actuate the sections of similar molds.

In testimony whereof we affix our signatures.

WALTER HENRY DRAKE.
JAMES JOSEPH DRAKE.
